UNITED STATES PATENT OFFICE.

JOHN OSCAR NEIKIRK, OF MORGAN PARK, ILLINOIS, ASSIGNOR TO RODGER BALLAST CAR COMPANY, A CORPORATION OF MAINE.

PLOW-CAR.

No. 904,214.

Specification of Letters Patent. Patented Nov. 17, 1908.

Application filed July 8, 1907. Serial No. 382,789.

To all whom it may concern:

Be it known that I, JOHN OSCAR NEIKIRK, a citizen of the United States, residing at Morgan Park, in the county of Cook and State of Illinois, have invented certain new and useful Improvements in Plow-Cars, of which the following is a specification.

The object of my invention is to provide a new and improved construction of the plow forming a part of cars used for ballasting and other purposes. As is well-known these cars are provided with plows secured beneath the floors of the cars and adapted to spread the material dumped upon the track.

Owing to the severe nature of the strains and shocks to which these parts are subjected it is necessary that they be constructed of great strength and so formed as to encounter the least resistance possible in spreading the ballast or other material.

In the drawing—Figure 1 is a side elevation of a plow constructed according to my invention, the outline of the car to which it is adapted to be attached being shown in dotted lines. Figs. 2 and 3 are detail views of the plow construction.

The body of the plow consists of converging plates 1 and 2, these plates preferably being curved in cross section, as illustrated.

At their forward ends the plates 1 and 2 are outwardly deflected forming flanges 3 and 4, said flanges in the assembled structure being parallel to each other. Instead of securing these flanges together directly, I provide for increased strength, and also secure a superior operation of the plow by passing a central plate 5 between the flanges 3 and 4.

The plate 5 lies in the axis of the plow and projects forward a considerable distance beyond the ends of the plates 1 and 2, thus forming a cutting edge which is adapted to readily enter the material on the track preparatory to the spreading action of the converging side plates 1 and 2. The center plate 5 and the side plates 1 and 2 are secured together by means of rivets passing

through all three of said parts. The strength of the structure is greatly increased by the reinforcing action of the center plate, and this plate also relieves the side plates of the initial shock and strain during the action of the plow upon the material on the track. The draw-bar 6 in the present instance is shown secured directly to the center plate 5.

The construction of the car and the mechanism for raising and lowering the plow may be of any preferred form and need not be described in detail as the invention herein claimed is limited to the construction of the plow and its attachment to the body of the car.

What I claim is:

1. In a car of the class described, a plow comprising converging side plates and a center plate between said side plates. 65

2. In a car of the class described, a plow comprising a center plate and side plates secured to the sides of said center plate and diverging therefrom.

3. In a car of the class described, a plow comprising converging side plates, parallel flanges on said plates at their adjacent ends, and a center plate between said side plates and projecting forward therefrom, said side plates being secured to each other and to the center plate. 70

4. In a car of the class described, a plow comprising converging side plates, parallel integral flanges on said plates at their adjacent ends, and a center plate between said side plates and projecting forward therefrom, said side plates being secured to each other and to the center plate. 80

5. In a car of the class described, a center plate, diverging side plates and a draw-bar secured to said center plate and to the body of the car. 85

JOHN OSCAR NEIKIRK.
